UNITED STATES PATENT OFFICE.

PETER NORD, OF LESTOCK, SASKATCHEWAN, CANADA.

SAFETY ATTACHMENT FOR SHIPPING PLATFORMS AND THE LIKE.

Application filed September 10, 1924. Serial No. 737,014.

To all whom it may concern:

Be it known that I, PETER NORD, a citizen of the Dominion of Canada, residing at Lestock, in the county of Last Mountain 5 and Province of Saskatchewan, Dominion of Canada, having invented new and useful Improvements in a Safety Attachment for Shipping Platforms and the like, do hereby declare the following is a specification:

10 This invention relates to improvements in a safety attachment for shipping platforms and the like having for a particular object to provide a device of the character described which will positively prevent the 15 closing of the shed doors without first elevating the platform, thus removing a constant danger to the freight men.

A further object is to provide such a device in the form of a hook that will hold 20 the platform in raised position or support it in lowered or operating position.

A further object is to provide such a device of simple construction, that may be readily applied and being capable of manufacture at a reasonable cost is thus rendered 25 commercially desirable.

To the accomplishment of these and related objects, my invention resides in the construction, combination and arrangement 30 of the various cooperating elements as shall be hereinafter more fully described, illustrated in the accompanying drawings and pointed out in the claims hereunto appended.

35 In the drawings, forming a part of this disclosure:—

Fig. 1 is a fragmentary section of the warehouse, showing the platform lowered, the door open and the relative position of a 40 freight car on the siding.

Fig. 2 is a similar section of the warehouse, showing the platform elevated and the door closed.

Fig. 3 is a perspective of the platform 45 retaining hook; and

Fig. 4 is a perspective of the simplified form of hook.

As many painful accidents have occurred 50 by train men contacting with the warehouse platforms that were not elevated through carelessness on the part of the employees at the warehouse and as it is generally experienced that thoughtlessness is the chief cause of such accidents, often resulting in fatalities, I have designed this hook, 55 to hold the platform in raised position or to

rest on the raised platform, that will positively prevent the closing of the door unless the platform is raised, thus necessitating the raising of said platform and the removal of 60 this constant danger before the watchman, caretaker or other warehouse employee can close the siding fronting doors.

Referring particularly to the drawings 65 wherein like characters designate like parts throughout the several views, the numeral 5 indicates the warehouse in general, 6 indicates the door and 7 the platform, all of which are of conventional design, the door or doors 6 being hinged and the platform 70 7 also hingedly connected a short distance below the door or even with it.

Hinged to the jam or jammed facing 8 is provided my safety attachment hook 9 being 75 T-headed as indicated at 10 where it is connected by the pin or bolt 11 to the jam facing 8. It is only when the body or stem of the hook 9 is in horizontal position and the arms of the T-head 10 consequently in vertical position when the door jam is cleared 80 to allow the closing of the door 6. At all other times, as when the hook is supporting the platform, as indicated in Fig. 1, the T-head 10 interferes with the jam and restricts the 85 closing of the door.

When the platform is elevated, as illustrated in Fig. 2, and the hook 9 is resting on the top of the platform 7, the arms 10 are arranged vertically and no obstruction 90 is offered the door which may be closed.

The form of hook illustrated in Figs. 1, 2 and 3 takes the form of my safety appliance and platform support combined, being 95 of the extendible type, but in practice it may be found more practical to use the conventional chain or rod support for the platform and the simplified safety hook 12 as illustrated in Fig. 4: The sole function of this hook being to retain the platform in elevated position on which it rests and in 100 which position the T-head 13 will be maintained in vertical position allowing of the closing of the doors.

From the foregoing description taken in 105 connection with the accompanying drawings, it will be manifest that a safety attachment for shipping platforms is provided which will fulfil all the necessary requirements of such a device, but as many changes could be made in the above description and many apparently widely different 110 embodiments of my invention constructed

within the scope of the appended claims without departing from the spirit or scope thereof it is intended that all matters contained in the said accompanying specification and drawings shall be interpreted as illustrative and not in a limited sense.

What I claim as new and desire to secure by Letters Patent is:—

1. A device of the character described adapted to retain a shipping platform in elevated position comprising a body to rest on the top of said platform with the depending end to embrace said platform pivoted to the warehouse, the remote end being provided with a T-head at said connection, said T-head being adapted to interfere with the door when said hook is moved from horizontal position as and for the purpose specified.
- 15 2. In combination with a warehouse, a safety attachment of the character described comprising an extendible hook, adapted to support and retain a shipping platform, hingedly connected to said warehouse at the

remote end and provided with a door interfering T-head at said connection, as and for the purpose specified.

3. A device of the character described adapted to retain a shipping platform in elevated position comprising a body to rest on the top of said platform with the depending end to embrace said platform pivoted to the warehouse, the remote end being provided with a T-head at said connection, said T-head being adapted to interfere with the door when said hook is moved from horizontal position as and for the purpose specified.

4. A safety attachment of the character described, comprising an extendible hook adapted to support and retain a shipping platform hingedly connected at the remote end and provided with the door interfering T-head at said connection, as and for the purpose specified.

In testimony whereof I hereunto affix my signature.

PETER NORD.
